UNITED STATES PATENT OFFICE.

PETER H. FELKER, OF ST. LOUIS, MISSOURI.

DESIGN FOR AN ANGLER'S RING.

SPECIFICATION forming part of Design No. 27,912, dated November 30, 1897.

Application filed June 2, 1897. Serial No. 639,172. Term of patent 7 years.

To all whom it may concern:

Be it known that I, PETER H. FELKER, a citizen of the United States, residing at St. Louis, in the State of Missouri, have invented a new and original Design for Anglers' Clearing-Rings, of which the following is a specification.

The accompanying drawing, forming part of this specification, is a view in elevation of an angler's clearing-ring, showing my design.

As shown in the drawing, the leading or material feature of the design consists in an angler's ring A, which when closed has the general appearance of a solid ring, the metal

composing the ring being circular in cross-section, smallest in diameter at the top B, where it is provided with a rounded radially-projecting lug C, and gradually increasing in diameter to the bottom D, where it is largest.

Having thus fully described my invention, what I claim as new, and desire to secure by Letters Patent of the United States, is—

The design for an angler's ring, as herein shown and described.

PETER H. FELKER.
